US0D1107605S

(12) **United States Design Patent** (10) **Patent No.:** **US D1,107,605 S**
Soni (45) **Date of Patent:** **** Dec. 30, 2025**

(54) **FRONT LOWER GRILLE FOR AUTOMOBILE**

(71) Applicant: **VOLVO CAR CORPORATION**, Gothenburg (SE)

(72) Inventor: **Nirmit Soni**, Gothenburg (SE)

(73) Assignee: **VOLVO CAR CORPORATION**, Gothenburg (SE)

(**) Term: **15 Years**

(21) Appl. No.: **29/934,722**

(22) Filed: **Mar. 27, 2024**

(30) **Foreign Application Priority Data**

Sep. 28, 2023 (EM) 015035562-0010
